United States Patent Office

Des. 220,803
Patented May 25, 1971

220,803

SALES TERMINAL

Ronald Segall, Los Angeles, Calif., assignor to Scantlin
Electronics, Inc., Los Angeles, Calif.

Filed Feb. 20, 1970, Ser. No. 21,552

Term of patent 14 years

Int. Cl. D14—02

U.S. Cl. D26—5

FIG. 1.

FIG. 2.

*FIG. 3.**FIG. 4.**FIG. 5.*FIG. 1 is a perspective view of a sales terminal showing my new design;

FIG. 2 is a top plan view thereof;

FIG. 3 is a front elevational view;

FIG. 4 is a side elevational view; and

FIG. 5 is a rear elevational view.

For convenience of illustration, some of the keys have either been omitted or not completed on the keyboard in FIGS. 1 and 2.

I claim:

The ornamental design for a sales terminal, as shown and described.
